UNITED STATES PATENT OFFICE.

ALBERT M. AHERN, OF ST. LOUIS, MISSOURI.

SMOKE-PRODUCING DEVICE FOR ROUTING WILD ANIMALS.

1,140,015.

Specification of Letters Patent.

Patented May 18, 1915.

Application filed October 17, 1912. Serial No. 726,228.

To all whom it may concern:

Be it known that I, ALBERT M. AHERN, a citizen of the United States of America, and a resident of the city of St. Louis, in the 5 State of Missouri, have invented certain new and useful Improvements in Smoke-Producing Devices for Routing Wild Animals, of which the following is a full, clear, and exact description, reference being had to the 10 accompanying drawings, forming a part of this specification.

My invention relates to a device that may be utilized to produce a quantity of dense smoke and deliver it into the dens of wild 15 animals, for the purpose of driving them therefrom, in order that they may be captured; and the invention has for its object the production of a device of this kind in which a large volume of smoke may be acquired and be forcibly expelled from the 20 device with a minimum loss of energy, or expelling force.

Figure I is a top or plan view of my smoke producing device. Fig. II is an enlarged 25 longitudinal section of the smoke chamber and smoke conducting members, taken on the line II—II, Fig. I, with the bellows of the device shown in side elevation. Fig. III is a cross section taken on line III—III, 30 Fig. I.

In the accompanying drawings: A designates a bellows, of any common form, that is adapted to receive air, and from which the air is expelled through the nozzle *a* 35 having a flanged flaring exit.

B designates a smoke chamber, that is preferably in the form of a cylinder and in which may be placed a desirable quantity of inflammable material of slow combustion, 40 and from which a quantity of smoke may be produced during combustion of the material. The material referred to may, for instance, be fibrous material, or the like, which will burn very slowly and is susceptible of 45 smoldering while undergoing combustion, in order that a considerable quantity of smoke may be derived within the smoke chamber with a minimum amount of combustion. The smoke production may be accelerated 50 and its effect amplified by the presence of sulfur, or other material, which will not only result in the production of smoke, but will also create obnoxious fumes.

The end of the smoke chamber B adjoining the bellows A is closed by a head 1, which constitutes a stopper for the chamber, and

is preferably removably connected to the chamber body, in order that it may be separated therefrom to permit the introduction into the chamber of the material that is to be consumed for the production of smoke. 60 As shown in the drawings, the head 1 is formed with a flange 2 which is inturned and seamed to a peripheral flange of a collar, that fits within the cylindrical body of the 65 chamber B and is provided with radial headed studs 3, the outer heads of which enter into and work in the bayonet slots 4 in the cylindrical body to lock the head to said body and retain the parts in engagement 70 while the device is in use. The head 1 is suitably connected to the nozzle *a* of the bellows A by a neck fitting around the flanged flaring exit, and said head has secured to it a flap valve 5, which normally 75 occupies a position against the flanged flaring exit at the forward end of the nozzle *a* and is held in such position by a leaf spring 6. The flap valve 5 is preferably made of asbestos, or other suitable non-combustible 80 material; and, while it is of such flexibility as to enable it to be forced away from the end of the bellows nozzle under pressure of air from the bellows, it is susceptible of being returned to its normal position by the 85 leaf spring 6, in order that the flame, or hot products of combustion within the combustion chamber B may not be permitted to enter into the bellows A.

The forward end of the smoke chamber B 90 is closed by a head 7, which is provided with a central perforated exit member 8, through which smoke may be discharged from said chamber. The head 7 carries a tapering smoke conducting nozzle 9 that has a flaring 95 inner end which surrounds the perforated exit member 8. The nozzle 9 in turn receives an extension nozzle 10 that may be of any desirable length, suitable to convey smoke passing therethrough to considerable distance into the hole or passageway leading to the den of an animal it may be desired to "smoke out" by the use of my smoke producing device.

In the use of my device, a quantity of 105 slowly combustible and smoke producing material is introduced into the smoke chamber B, when the head with its collar 2 is separated from the body of the chamber B, and such material is then ignited. The removable head of the smoke chamber is next attached to the body of the chamber, and 110

the bellows A is operated, whereby air is forcibly delivered into said chamber to create a draft therein, that will result in slow combustion of the material in the smoke chamber, whereby a quantity of smoke is produced therein and forced therefrom through the perforated exit member 8, into and through the delivery nozzles 9 and 10, from the latter of which it passes into the entranceway to the den of an animal it may be desired to rout by the use of my device.

The smoke chamber B is provided with a handle 11, by which the smoke producing device may be conveniently carried.

15 I claim:—

The combination in a smoke producing de-

vice, of a bellows having a discharge nozzle formed with a peripheral flange providing a flat valve seat at its end, a combustion chamber head having a neck surrounding 20 said discharge nozzle and closely fitted thereto, the said peripheral flange being arranged within said head and closely fitted to the inner face thereof so as to firmly secure said head to said nozzle, and a spring controlled valve secured to said head and seated on the peripheral flange at the end of said nozzle.

ALBERT M. AHERN.

In the presence of—

H. G. COOK,

E. B. LINN.
